BED-MOTION IN PRINTING-MACHINES.

1,111,604.

Specification of Letters Patent. Patented Sept. 22, 1914.

Application filed May 4, 1911. Serial No. 825,050.

To all whom it may concern:

Be it known that we, ROBERT MIEHLE and ROBERT F. MIEHLE, Jr., citizens of the United States, and residents of Chicago, in the county of Cook and State of Illinois, have invented a certain new and useful Improvement in Bed-Motions in Printing-Machines, of which the following is a specification.

The invention relates to that class of printing machines in which the "form" is carried upon a bed having a reciprocating movement under the impression-cylinder and is an improvement on the bed motion for printing machine for which Letters Patent of the United States No. 322,309 were issued to Robert Miehle on the 14th day of July, in the year 1885. In the above mentioned patent, the drive gearing is so arranged that the intermediate driving gear which meshes with the cylinder gear is of the same size as the latter. It is desirable to have this intermediate gear of a large proportion so as to make a more durable gear mesh direct between the bed motion shaft drive gear and the type or form bed. In the device shown in said Patent No. 322,309, the said intermediate gear is secured to a shaft which has another gear at its inner end under the type bed, meshing with a gear secured to the bed motion drive gear shaft upon which the bed motion gear also is secured. This arrangement of driving the bed motion shaft necessitates that the pitch diameters of the gears under the bed be reduced in order to place them in that position. When so reduced, the moving of the bed motion gear into and out of mesh with the racks causes the acceleration and retardation of the bed motion reversing crank on said gear to be abnormally increased on account of the reduced pitch diameters of the gears which is objectionable. This reduction of the pitch diameters also places a greater strain upon the teeth, making them wear out more rapidly, thus causing lost motion between the gears and an undesirable back lash of the reversal crank in the slot at the time it brings the type bed to a stop and starts it in the opposite direction.

The invention has for its objects: first, to provide means for driving the bed motion shaft direct from the outside of the type bed or press frame, the driving gears being

of normal pitch diameters and always in mesh; second, to arrange the bed motion drive gears so that the acceleration and retardation of the crank (caused by the up and down motion of the bed motion frame) is applied at the ends of the stroke which will benefit the speed of the machine and make possible the printing of a somewhat longer form. In the gear mechanism disclosed in Letters Patent of the United States No. 790,574 issued to W. S. Huson under date of May 23, 1905, the driving gear is in mesh with the cylinder gear, said intermediate gear being secured to a shaft having another gear at its inner end under the type bed, the latter gear meshing with a transmission gear which has a position on the side of the gear secured to the bed motion driving gear shaft. This arrangement imparts an accelerated motion to the crank at the end of the printing stroke and a retarded movement to the crank at the end of the non-printing stroke described more fully hereafter. However, in said Patent No. 790,574, the driving gearing under the bed is also of a reduced pitch diameter and has all of the objectionable features pointed out heretofore in Patent No. 322,309. In our new arrangement, we secure the acceleration at the end of the printing stroke and the retardation at the end of the non-printing stroke, at the same time retaining the full pitch diameters of the drive gearing which the above mentioned patents do not, as well as arranging the cylinder drive gear favorably with respect to the bed motion drive gear so that they occupy a compact space outside of the press frame thus allowing easy access to all parts of the machine.

We attain these objects by the mechanism illustrated in the accompanying drawings, in which—

Figure 1 is the gear side view of a printing press in elevation. Fig. 2 is a rear end view of Fig. 1, partly in section. Figs. 3 and 4 show detailed construction of bed motion rocker frame. Fig. 5 shows detailed construction of driving gears. Fig. 5^a shows modification of driving gears. Figs. 6, 7, 8, and 9 show detailed operation of mechanism for retarding, stopping and accelerating the movement of the type bed.

Similar numbers of reference indicate like parts in the several views.

Referring to the drawings for a detailed description of the construction, 1 indicates a rack-frame fixedly secured to the under side of the reciprocating type bed, 2. The 5 rack-frame is provided with upper and lower racks 3 and 4, with which the driving gear 5 alternately engages. The form here shown is similar to the one disclosed in United States Patent No. 322,309 referred to, in which a straight shoulder 6 is employed at either end in juxtaposition to an inner shoulder or gate 7, pivoted so as to allow the reversing crank or wrist-pin 8, carried by the driving gear, to engage between the shoulders on the reversal of the bed in a well known manner. The operation of the gates 7 and 7' is well known and described in above mentioned patent, making it unnecessary to describe them further 20 here.

The means for driving the bed motion shaft direct from the outside of the type bed or press frame is as follows: At the outer end of the bed motion shaft 9, is the 25 pinion 10 of the same size as the drive pinion 5, said pinion 10 being in mesh with the internal gear 11. The internal gear 11 is bolted to the intermediate gear 12' which is driven by the small pinion on the main 30 drive shaft 13. The intermediate cylinder gear 12 is also bolted to the intermediate gear 12' and is in direct mesh with the cylinder gear 14 which is secured to the cylinder shaft, thus imparting motion to the 35 cylinder 15. However, we do not limit ourselves to this construction as the cylinder gear may be in direct mesh with the intermediate driving gear 12', thus eliminating the intermediate cylinder gear 12. Also, 40 ring gear 11 may be formed integrally with said intermediate gear 12' in which case the cylinder gear would mesh directly with the teeth on said integral gear (as shown in Fig. 5a) in which the outer periphery of the 45 ring gear is provided with teeth for driving. This arrangement also gives a broader driving surface. The cylinder is journaled in the side frame 23. This arrangement of gears has several advantages. Having the 50 intermediate cylinder gear 12 bolted to the intermediate gear 12' but not engaging the main drive pinion 13', on shaft 13, enables us to vary the pitch diameter of intermediate cylinder gear 12, thus giving wider latitude in the position of the shaft 24 upon which the intermediate gear 12' is mounted. Said intermediate gear 12 may be released from intermediate gear 12' and turned 55 loosely on the hub of said central member to test the travel of the cylinder with the form. When it is desirable to print a longer form in a four roller press, using but three of the rollers, it is necessary to adjust the cylinder so that the grippers will 60 have their proper relative position with the

longer form. To accomplish this adjustment, intermediate cylinder gear 12 is released from the central member which is then turned until the original bolt holes in it correspond with holes 34 on gear 12 (as shown in Fig. 1) and bolted in this position. As shown in Fig. 1, 35 indicates form inking rollers; 36 indicates beginning of form when surface of form is inked by all four rollers; 37 indicates beginning of form when longer 75 form is inked by three rollers only; 38 indicates the "grippers" on surface of cylinder.

The detailed construction of gears 11, 12' and 12 is shown in Fig. 5, in which intermediate gear 12' is the central member fixed to the shaft 24. The internal gear 11 is a ring gear bolted to said intermediate gear 12'. The intermediate cylinder gear 12 is loosely mounted about the hub of the intermediate gear 12' and bolted to it as shown.

The circumference of the impression cylinder 15 is equal to the pitch of the internal gear 11 and each makes two complete revolutions to one complete backward and forward stroke of the type bed, but we do not limit ourselves to such relative dimension. As stated, driving pinion 5 and pinion 10 (respectively at inner and outer ends of the bed motion shaft) are of the same size and each make three complete revolutions to one complete backward and forward stroke of the type bed. These pinions 5 and 10 are rotated in one direction only.

The main drive shaft 13 is supported by 100 the upright brackets 30 and the shaft 24 is supported by the upright bracket 30', and is journaled in the bearing 24'. The brackets 30 and 30' form part of the base frame 23, thus forming a frame or bracket 105 connection around the intermediate gear to the side frame 23.

It is evident that by having the intermediate gear for driving the bed motion shaft outside the type bed or press frame, larger 110 and consequently more durable gears can be used and without reducing the pitch diameters of the gears, thus attaining better control of the type bed with the reversing crank. The advantage of using an internal 115 gear for communicating motion to the bed motion shaft lies in the fact that more of the teeth are in mesh at all times and that in rolling they draw away more slowly, thus eliminating friction, and consequently wear 120 and tear, and adding to the life of the gears.

The lifting and lowering of the bed motion shaft 9 to engage the drive pinion 5 with the racks 3 and 4 alternately is accomplished by means of the bed motion rocker 125 frame in the following manner: The bed motion rocker frame consists of a bearing 16 in which is journaled the bed motion shaft 9; an arm 17 which has a stud and friction roller 18 in the cam groove 19' of 130

the bed motion cam 19 mounted on shaft 31; and fulcrum extensions 20 and 21 which have bearing in the standard 22 and the side frame 23. In this particular instance, the 5 fulcrum extensions 20 and 21 are in direct line with the shaft 24. However, we do not limit ourselves to this construction as the fulcrum center may be placed at any point on the line YY' (which cuts through the 10 center of the bed motion shaft when it is in position about midway between the upper and lower racks, and the center of the shaft 24) as shown in dotted construction 21' and 22' in Fig. 1. That is, the bed motion shaft 15 is on a line that shifts or oscillates and is radial with respect to the shaft 24. In Figs. 3 and 4, the detailed construction of the bed motion rocker frame is shown. The extension 20 and 21 are formed by fitting a shaft 20 into the bed-motion rocker frame, and by sliding this shaft out the rocker-frame can be easily removed from the press frame.

Motion is applied to the bed motion cam as follows: Meshing with the intermediate 25 gear 12' is the pinion 25 which is secured to the short shaft 32. At one end of said shaft 32 is secured a smaller gear 26 which meshes with the pinion 27 secured to the short shaft 33. At one end of said shaft 33 is secured 30 the small pinion 28 which meshes with the cam shaft gear 29. The cam shaft gear 29 is secured to the cam shaft 31, thus driving the bed motion cam 19. As the cam 19 rotates, the stud 18 slides in cam groove 19', 35 lifting and lowering the arm 17, thus lifting and lowering the bed motion shaft 9 which carries with it the pinions 5 and 10, the former meshing with top and bottom racks 3 and 4 as stated above.

40 As stated, the second object of this invention is to arrange the bed motion drive gear so that the acceleration and retardation (caused by the up and down motion of the bed motion shaft) is applied at the ends of 45 the stroke which will benefit the speed of the machine and make possible the printing of a somewhat longer form. Near the end of the non-printing stroke, as shown in Fig. 6, when the reversing crank or wrist-pin 8 enters the slot formed by the shoulders 6' and 7' and the pinion leaves the lower rack 4, the working of the stud 18 over the portion *f* of the cam groove 19' (substantially one-sixth of a revolution of the cam 19—the said 50 cam making one complete revolution to three complete revolutions of the driving gear 5) causes the bed motion frame to lift the bed motion shaft 9 which, of course, carries up with it pinions 5 and 10, bringing the reversing crank 8 to the position shown in Fig. 7. This lifting of the bed motion shaft 55 interferes with the uniformity of the rotary velocity of pinions 5 and 10, and the reversing crank 8, imparting to them turning effort in the opposite direction to that in

which they would normally turn, thus momentarily checking their rotary velocity which aids to slow down the movement of the type bed 2.

Near the end of the printing stroke, as 70 shown in Fig. 8, when the reversing crank or wrist-pin 8 enters the slot formed by the shoulders 6 and 7 and the pinion 5 leaves the upper rack 3, the working of the stud 18 over the portion *h* of the cam groove 19' (substantially one-sixth of a revolution of said cam 19) causes the bed motion frame to lower the bed motion shaft 9 which, of course, brings down with it pinions 5 and 10, bringing the reversing crank 8 to the position shown in Fig. 9. This lowering of the bed motion shaft also interferes with the uniformity of the rotary velocity of pinions 5 and 10 and reversing crank 8, imparting to them turning effort in the same direction 85 as that in which they would normally turn, thus accelerating their rotary velocity which accelerates the movement of the type bed 2. The cam action occurring at the time it does, just when the type bed is about to slow up 90 because of the reversing crank 8 entering the slot as described, causes this acceleration to drive the type bed a little farther at uniform speed making it possible to print a somewhat longer form than if the said acceleration had not been obtained. The pinions 5 and 10 and the shaft upon which they are mounted together constitute a form of gear element, such gear element including 95 the two separated pinions 5 and 10 that are 100 mechanically fixed with respect to each other, the gear parts 5 and 10 being separated merely for structural purposes, and we therefore, do not limit ourselves to a gear element in which the parts 5 and 10 are 105 distinct.

We do not limit ourselves to the specific construction herein shown and described for imparting the to and fro motion to the type bed by the bed motion driving pinion and reversing crank as we are aware that many changes may be made in practising our invention by those who are skilled in the art without departing from the scope of our invention as expressed in the claims.

Having thus fully described our invention, what we claim and desire to secure by Letters Patent is:

1. In a printing press, the combination with a form bed; of means for reciprocating 120 said bed including a shaft; devices operated by said shaft for moving the bed to and fro; a movable support carrying said shaft, means for shifting said support; a gear on the outer end of said shaft; and an internal 125 gear meshing with the gear on the outer end of the said shaft; said gear being so positioned relative to said internal gear that the shifting movements of the gear relative to the internal gear cause an accelerated move- 130

- ment of the bed at one end of its stroke, and a retarding movement of the bed at the other end of the stroke.
2. In a printing press, the combination with a form bed; of means for reciprocating said bed including a gear element; means operated by said element for moving the bed to and fro; a movable support carrying said gear element; means for shifting said support to cause the gear element to move the bed in either direction; and an internal gear meshing with said gear element, said gear element being so positioned relative to said internal gear that the shifting movements of the gear element relative to the internal gear cause an accelerated movement of the bed at the end of the printing stroke, and a retarding movement of the bed at the end of the non-printing stroke.
3. In a printing press, the combination with a form bed; of means for reciprocating said bed, including a shaft and devices operated by said shaft for moving the bed to and fro; a pivoted support carrying said shaft; means for shifting said support; a gear on the outer end of said shaft; and an internal gear meshing with the gear on the outer end of said shaft, the fulcrum of the said support being positioned on a line passing approximately through the axes of said gears.
4. In a printing press, the combination with a form bed; of means for reciprocating said bed including a shaft and devices operated by said shaft for moving the bed to and fro; a pivoted support carrying said shaft; means for shifting said support; a gear on the outer end of said shaft; and an internal gear meshing with the gear on the outer end of the shaft, the fulcrum of the said support being positioned substantially in line with the axis of said internal gear.
5. In a printing press, the combination with a form bed; of means for reciprocating said bed, including a shaft and devices operated by said shaft for moving the bed to and fro; a pivoted support carrying said shaft; means for shifting said support; a gear on the outer end of said shaft; and an internal gear meshing with the gear on the outer end of said shaft, the fulcrum of the said support being positioned on a line passing approximately through the axes of said gears; said gear being so positioned relative to said internal gear that the shifting movements of the gear relative to the internal gear cause an accelerated movement of the bed at the end of the printing stroke, and a retarding movement of the bed at the end of the non-printing stroke.
6. In a printing press, the combination with a form bed; of means for reciprocating said bed including a gear, devices cooperating with said gear for moving said bed to and fro; a shaft supporting said gear and extending to a point outside of said
- shaft; means for shifting said support; a gear on the outer end of said shaft, and an internal gear meshing with the gear on the end of the shaft, the fulcrum of the said support being positioned substantially in line with the axes of said internal gear; said gear being so positioned relative to said internal gear that the shifting movements of the gear relative to the internal gear cause an accelerated movement of the bed at the end of the printing stroke, and a retarding movement of the bed at the end of the non-printing stroke.
7. In a printing press, the combination with a form bed, of means for reciprocating said bed including a shaft extending from a point beneath to a point outside of said bed, devices operated by said shaft for moving the bed to and fro, an oscillating frame carrying said shaft, means for oscillating said frame to cause reverse movement of the bed, a gear on the outer end of said shaft, and an internal gear meshing with the gear on the end of the shaft, the fulcrum of the said oscillating frame being positioned inside of the pitch diameter of said internal gear.
8. In a printing press, the combination with a form bed, means for reciprocating said form bed including a shaft extending from a point underneath the bed to a point at one side thereof, a gear carried by said shaft, spaced racks carried by said bed and located one above and the other below said gear, an oscillating frame for supporting said shaft, means for oscillating said frame, whereby said gear is caused to engage first one rack and then the other, a gear on the outer end of said shaft, an internal gear at one side of said bed and meshing with the gear on the outer end of said shaft, the axis of said oscillating frame being substantially in line with the axis of said internal gear.
9. In a printing press, the combination of a form bed, and means for reciprocating said bed including a shaft extending from a point underneath the bed to a point outside thereof, devices carried by the inner end of said shaft for moving said bed to and fro, a gear on the outer end of said shaft at one side of said bed, an internal gear at one side of said bed meshing with and imparting a continuous rotary movement to the gear on the outer end of the shaft, said internal gear having gear teeth on its outer periphery, a driving pinion meshing with the gear teeth on the outer periphery of said internal gear, and a cylinder gear also meshing with the gear teeth on the outer periphery of said internal gear.
10. In a printing press, the combination with a form bed, of means for reciprocating said bed, including a gear, devices cooperating with said gear for moving said bed to and fro, a shaft supporting said gear and extending to a point outside of said

bed, a second gear mounted on the end of said shaft, an internal gear at one side of said bed meshing with a gear on the outer end of said shaft, the outer periphery of 5 said internal gear being provided with gear teeth, a supporting member to which said internal gear is secured, said supporting member having teeth in line with the gear teeth on the outer periphery of the internal 10 gear.

11. In a printing press, the combination with the form bed, of means for reciprocating said bed including a gear, devices co-operating with said gear for moving the 15 bed to and fro, a shaft supporting said gear

a second gear on the outer end of said shaft, an internal gear at one side of the bed meshing with said gear on the end of the shaft, the outer periphery of said internal gear being provided with gear teeth, a central 20 supporting member to which said internal gear is bolted, a third gear bolted to said central supporting member, and rotatably adjustable with respect to said central member.
